UNITED STATES PATENT OFFICE.

HENRY F. SCHMIDT, OF PHILADELPHIA, PENNSYLVANIA, ASSIGNOR TO WESTINGHOUSE ELECTRIC & MANUFACTURING COMPANY, A CORPORATION OF PENNSYLVANIA.

DREDGER PUMP.

Application filed December 6, 1922. Serial No. 605,314.

My invention relates to a pump of the propeller type particularly adapted for use in dredging and in similar operations, and it has for its object to provide apparatus of the character designated, which shall be simple, rugged and efficient in construction and operation; which shall be effective to crush or to reduce by attrition large rocks or other foreign bodies attempting to pass therethrough; and in which all parts subject to wear or breakage may be readily replaced.

In the accompanying drawing, Figure 1 is a side view, partially in section and partially in elevation, of a pump constructed in accordance with my invention; Figure 2 is a sectional view taken on the plane II—II of Figure 1; and Figure 3 is a similar view taken on the plane III—III of Figure 1.

In the dredging field and in similar applications, it has long been desirable to employ a propeller-type pump on account of its simplicity, compactness and high capacity, together with good efficiency, but such an application has been dismissed because of the liability of the propeller to jamming and breakage because of the impact of boulders and other foreign substances thereagainst.

In accordance with the present invention, I provide a propeller pump with a casing having internal teeth adapted to coact with the pump blades in order to crush or to reduce by attrition large boulders attempting to pass through the device and I, furthermore, employ such clearances that the crushed or reduced particles shall not clog subsequent to passing through the propeller.

Referring to the drawing for a more detailed understanding of my invention, I show an inlet casing at 5, preferably curved in general contour so as to permit the introduction of a suitable propeller shaft 6 thereinto through a suitable elongated boss 7.

The casing 5 terminates in a plane flanged opening at 8 and the shaft 6 carries a propeller member 9 arranged to rotate within the member 5 at some distance back from the plane of the opening 8, the blades preferably having a blunt intake edge and a sharp discharge edge as shown at 9'.

The member 5 is suitably recessed back from the opening 8 for the reception of a lining member 10 carrying inwardly projecting teeth 11—11 positioned somewhat back of

the propeller 9, this lining member preferably being formed in a plurality of segments 10' for facility in casting.

A divergent discharge member 12 is adapted to be mounted opposite the flanged opening 8 and carries guide vanes 13—13 adapted to prevent eddying in the discharge stream as fully discussed in my co-pending application, Serial No. 371,648, filed Apr. 6, 1920, and assigned to the Westinghouse Electric & Manufacturing Company. The vanes 13—13 are carried between a lining member 14 seated within the member 12 and a centrally-disposed guide cone 15 which further acts to cause smooth, unbroken flow of the discharge stream. Preferably the lining member 14 is formed in a plurality of segments 14', each carrying its blade 13, for facility in manufacture. The cone 15 is provided with a bearing at 16 to carry the outer end of the shaft 6 so as to more firmly support the propeller 9.

The member 10 with the teeth 11—11, the member 14 with the vanes 13—13, and the propeller itself are preferably formed of material highly resistant to wear and breakage, such as chilled manganese, chromium or tungsten steel, and the configuration should be as simple as possible in order to permit ready casting and chilling. By forming all parts in small portions or segments, manufacture from these refractory alloys is made possible.

The discharge plane of the propeller 9 is spaced away from the inlet edges of the guide vanes 13—13 by a distance X greater than the minimum radial dimension Y of the discharge fluid passage for a reason to be herein after more fully pointed out.

Having thus described the arrangement of a structure constructed in accordance with my invention, the operation thereof is as follows:

When supplied with water and mud, the propeller 9 functions in the usual manner, the teeth 11—11 functioning somewhat as guide vanes to cause proper entry of the fluid to the propeller and the guides 13—13, together with the cone 15, facilitating a smooth, unbroken discharge.

When rocks and boulders of unreasonable size enter the device, they are hit by the propeller blades and thrown back against the teeth 11—11 with such force that they are either crushed and broken to such an extent

that they may pass on through the propeller, or they are continually thrown around between the blunt inlet propeller edges and the teeth 11—11 and rapidly reduced by attrition.

5 By making the dimension X greater than the dimension Y, as indicated, I insure that any fragment which is capable of passing through the propeller 9 shall not become jammed between the propeller and the inlet edges of the vanes 13—13.

Upon the breakage or undue wear of any of the members, the discharge member may be separated from the inlet member at the flanged joint shown, when the propeller 9 may 15 be removed from the end of the shaft 6 and the member 10 may be slipped out and replaced. Similarly, the member 14 may be renewed if desired.

While, in general, the clamping of the parts 20 together at the flanged joint prevents the rotation of the lining members 10 and 14, it will be obvious that they may be keyed in place if so desired in order to positively prevent rotation thereof.

25 While I have shown my invention in but one form, it will be obvious to those skilled in the art that it is not so limited, but is susceptible of various other changes and modifications, without departing from the spirit 30 thereof, and I desire, therefore, that only such limitations shall be placed thereupon as are imposed by the prior art or as are specifically set forth in the appended claims.

What I claim is:—

35 1. The combination with a propeller pump provided with an intake member, of crushing teeth mounted on the interior of said intake member and adapted to coact with the propeller blades in reducing foreign substances 40 attempting to pass through the pump.

2. The combination with a propeller pump enclosed in a casing and provided with an intake member, of a ring provided with inwardly extending teeth mounted within said intake 45 member, said teeth being adapted to coact with the blades of the propeller to reduce foreign substances attempting to pass through the pump.

3. The combination with a propeller pump 50 enclosed in a casing and provided with an intake member, of a ring formed in a plurality of distinct segments and provided with inwardly extending teeth mounted within said intake member, said teeth being adapted to coact 55 with the blades of the propeller to reduce foreign substances attempting to pass through the pump.

4. The combination with a propeller pump, 60 of a discharge member therefor provided with guide vanes for preventing eddying, the discharge plane of the propeller being spaced away from the inlet plane of said vanes a distance at least as great as the minimum radial dimension of the discharge fluid 65 passage.

5. In a propeller pump structure, the combination with an inlet member, of a propeller mounted near the discharge opening thereof, a discharge member coacting with said inlet member to provide a pump 70 casing, internal teeth in said inlet member positioned so as to coact with the propeller blades to reduce foreign bodies attempting to pass through the pump, and guide vanes within said outlet member adapted to prevent eddying in the discharge stream, the inlet plane of said guide vanes being spaced away from the discharge plane of said propeller a distance at least as great as the minimum radial dimension of the discharge fluid passage. 75

6. In a propeller pump structure, the combination with an inlet member, of a propeller mounted near the discharge opening thereof, a discharge member coacting with said inlet 80 member to provide a pump casing, internal teeth in said inlet member positioned so as to coact with the propeller blades to reduce foreign bodies attempting to pass through the pump, and guide vanes within said outlet member adapted to prevent eddying in the discharge stream, the inlet plane of said guide vanes being spaced away from the discharge plane of said propeller a distance at least as great as the minimum radial dimension of the discharge fluid passage, and said internal teeth and said guide vanes being carried by removable lining members, whereby they may be readily renewed upon wear or breakage. 90

100 7. In a propeller pump structure, the combination with an inlet member, of a propeller mounted near the discharge opening thereof, a discharge member coacting with said inlet member to provide a pump casing, internal 105 teeth in said inlet member positioned so as to coact with the propeller blades to reduce foreign bodies attempting to pass through the pump, and guide vanes within said outlet member adapted to prevent eddying in the discharge stream, the inlet plane of said guide vanes being spaced away from the discharge plane of said propeller a distance at least as great as the minimum radial dimension of the discharge fluid passage, and said internal teeth and said guide vanes being carried by removable lining members formed in separable segments, whereby they may be 110 readily renewed upon wear or breakage. 115

120 8. In a propeller pump structure, the combination with a curved hollow inlet member terminating in a plane opening, of a hollow boss projecting thereinto and surrounding a drive shaft carrying a propeller arranged to rotate in a plane parallel and adjacent to said discharge plane, a lining member within said inlet member and carrying a plurality of inwardly projecting teeth adapted to coact with the propeller blades in the reduction of foreign bodies attempting to traverse the 125 130

5 pump, and a divergent discharge member adapted to coact with said inlet member to provide a pump casing, said discharge member being provided with a plurality of internal guide vanes carried by a removable lining member.

9. In a propeller pump structure, the combination with a curved hollow inlet member terminating in a plane opening, of a hollow 10 boss projecting thereinto and surrounding a drive shaft carrying a propeller arranged to rotate in a plane parallel and adjacent to said discharge plane, a lining member within said inlet member and carrying a plurality 15 of inwardly projecting teeth adapted to coact with the propeller blades in the reduction of foreign bodies attempting to traverse the pump, a divergent discharge member adapted to coact with said inlet member to provide 20 a pump casing, said discharge member being provided with a plurality of internal guide vanes carried by a removable lining

member, the intake plane of said guide vanes being spaced away from the discharge plane of said propeller a distance at least as great 25 as the minimum radial dimension of the discharge fluid passage.

10. The combination with a rotary pump, of means within the casing and adjacent the inlet of the pump for reducing foreign substances by attrition. 30

11. The combination with a rotary pump, of abrasive means within the casing and adjacent the inlet of the pump for reducing foreign substances by attrition. 35

12. The combination with a rotary pump, of means providing an abrasive surface extending around the interior of the casing and adjacent the inlet of the pump for reducing foreign substances by attrition. 40

In testimony whereof, I have hereunto subscribed my name this 28th day of November, 1922.

HENRY F. SCHMIDT.
